UNITED STATES PATENT OFFICE.

EDWARD E. REDFIELD, OF GLENDALE, OREGON.

FIREARM.

1,233,603.

Specification of Letters Patent. Patented July 17, 1917.

Application filed September 8, 1916. Serial No. 118,962.

To all whom it may concern:

Be it known that I, EDWARD E. REDFIELD, a citizen of the United States, and residing in the city of Glendale, county of Douglas, 5 in the State of Oregon, have invented certain new and useful Improvements in Firearms, of which the following is a specification, reference being had to the accompanying drawings, forming a part hereof.

10 This invention relates mainly to magazine firearms of the "slide-action" type, in which the operations of extracting the empty shell, cocking the gun and placing a fresh cartridge in the chamber of the barrel are effected by the longitudinal movements of a grip-piece which is mounted to slide on the magazine-tube parallel with the barrel. The invention is shown and described herein as embodied in a shotgun, but it will be 15 evident, as this description proceeds, that the main features of the invention are not applicable solely to shotguns, but might be applied to rifles as well, and that some of the improvements are capable of use independently of each other and are not necessarily restricted in their application to a 20 firearm which embodies all of the improvements herein referred to.

One part of the invention is concerned 25 with the take-down or those features of construction which permit the barrel to be separated readily from the stock. The object of this part of the invention is to provide improved devices which avoid the use of any special, separate parts other than those which are incidental to other functions of the gun, and at the same time to insure the close and secure union of the parts when the gun is set up.

30 Another part of the invention relates to the breech mechanism, provision being made whereby the firing-pin is locked against movement at all times except when the parts of the gun are otherwise in firing position; 35 provision being also made whereby the accidental separation of the breech-block from the receiver, when the gun is taken down, is prevented.

Another part of the invention relates to 40 the lock mechanism, all of the parts of which are mounted on an assembly clip so that all parts of this mechanism may be assembled outside of the frame and may be placed and secured in position therein as a 45 unit, thus greatly facilitating the work of assembling the gun both for the manufac-

turer and for the repairer. Moreover, all of the parts of the lock mechanism are mounted, in such assembly clip, on two pins, the hammer-pin and the trigger-pin, thereby 50 simplifying and improving the construction. Provision is made whereby premature opening of the gun, in case of a hang-fire, is prevented, while the release of the parts, to permit opening, is accomplished 55 either by the voluntary movement of the hand or by the recoil. Improvements are also made with respect to the tripping of the slide-latch and the operation of the trigger-latch. The lifter is so operated as 60 to reduce to a minimum the friction on the cartridge while it is being inserted into the chamber of the barrel.

An exceedingly simple but highly effective device for controlling the feed of the 65 cartridges from the magazine is also provided.

Various other features of improvement will be referred to more particularly hereinafter.

In the accompanying drawings, in which the invention is illustrated,--

Figure 1 is a view in side elevation of the assembled gun.

Fig. 2 is a view partly in side elevation 85 as seen from the left hand side of the gun and partly in vertical section through the receiver and frame, on a much larger scale than Fig. 1, the parts being in readiness for firing.

Fig. 2^a is a detail view in transverse section on the plane indicated by the line 2^a—2^a.

Figs. 2^b and 2^c are detailed views of the 90 rear end portion of the slide-bar as seen from the side opposite to that shown in Fig. 2 and from above respectively.

Fig. 3 is a detail view of a portion of the lock mechanism showing the trigger, trigger-latch, hammer, hammer-latch, slide-latch and slide-latch lock, the rear end of the slide-bar being also shown.

Fig. 4 is a detail partly in side elevation 105 as seen from the right hand side of the gun and partly in longitudinal section through the frame and receiver, the parts being shown in the positions which they occupy when the gun has just been fired and before it is opened.

Fig. 5 is a view similar to Fig. 4 but showing the parts in the positions which they 110 occupy when the gun has been opened to

eject the empty shell and to place a fresh cartridge in the chamber of the barrel.

Fig. 6 is a view in section on the horizontal plane indicated by the broken line 6—6 of Fig. 2.

Fig. 7 is a view in transverse section on the plane indicated by the line 7—7 of Fig. 4.

Fig. 8 is a view of the lifter.

Fig. 9 is a detail view in section of the lifter, on the irregular plane indicated by the broken line 9—9 of Fig. 8.

Fig. 10 is a view in perspective of the assembly clip.

Fig. 11 is a view in perspective of the slide-bar latch.

Fig. 12 is a view in perspective of the trigger-latch.

Fig. 13 is a view in perspective of the hammer.

Fig. 14 is a view similar to Fig. 1 but showing the gun taken down.

The barrel *a*, chambered as usual to receive the cartridge, the magazine-tube *b*, (except as hereinafter indicated), in which the cartridges are placed and are pressed to the rear by a spring follower *b'*, the receiver *c*, the frame *d* (except as hereinafter indicated), and the stock, are constructed substantially as usual in shotguns of the type referred to.

The receiver *c* has at its rear upper end a rearwardly and downwardly projecting beveled hook *c'* adapted to engage a corresponding beveled recess *d'* formed in the under side of the upper wall of the frame near its forward end. The lower rear corners *c*² of the receiver are rounded off in the arc of a circle and the corresponding inner angles *d*² of the frame are correspondingly rounded off. The forward end of the frame has an upwardly projecting, beveled lug *d*³ to enter a corresponding beveled recess *c*³ in the under side of the receiver near its forward end. The extreme forward end of the frame is formed as a ring through which the cartridges are pushed rearwardly upon the lifter, the ring being slightly tapered interiorly for coöperation with the extreme rear end *b*², also tapered, of the magazine-tube *b*, which is threaded, as at *b*³, just in advance of the tapered end, to engage a threaded opening in the front lower end of the receiver *c*. In setting up the gun the beveled hook *c'* is first engaged with the corresponding recess *d'* and the parts are then brought together as on a hinge. The rolling of the curved shoulder *c*² upon the forwardly projecting portion of the frame *d* and into the rounded angle *d*², forces the hook *c'* firmly into the recess *d'* and insures its retention, while the beveled lug *d*³ at the forward end of the frame, coacting with the beveled recess *c*³, forces the rear end of the receiver 65 rearwardly into close contact with the for-

ward end of the upper portion of the frame, thus insuring a close union of the parts, which are held in this position by screwing the magazine-tube rearwardly to cause its tapered rear end to coact with the interiorly tapered ring at the extreme forward end of the frame, the proper alinement of the parts being also thus insured.

The receiver *c* has near its rear end an interior shoulder *c*⁴, against which the breech-block *e* abuts in the firing position, so that the breech pressure is taken entirely by the receiver and puts no strain on the take-down devices. In the opening of the gun the breech-block first drops at its rear end to clear the shoulder *c*⁴ and then passes rearwardly below the shoulder into the chamber in the frame. The breech-block *e* carries the ejector devices which may be of usual construction. It also carries the usual firing-pin *f* and a bell-crank lever *g* provided with a lug *g*¹ to engage a notch *f*¹ in the firing-pin and lock the pin against movement except when all of the parts are in firing position. The locking lever *g* is normally held in locking position by a spring *g*² and is moved to release the firing-pin by the slide-bar, as hereinafter explained.

The grip piece *h* is mounted upon the magazine-tube *b* as usual and has extended rearwardly therefrom a slide-bar *h*' which has at its rear end an inwardly projecting lug *h*² to enter the cam-slot *e*' in the corresponding side of the breech-block. As the slide-bar reciprocates in the usual manner and as it approaches the extreme forward limit of its movement it engages the lower end of the bell-crank locking lever *g* and moves it to disengage its lug *g*¹ from the notch *f*¹ of the firing-pin and thereby place the firing-pin in readiness for firing. As the slide-bar approaches the extreme rearward limit of its movement, the breech-block then moving downwardly in the frame, the lug *h*² engages the other arm of the bell-crank lever and moves it in the opposite direction to cause its lug to engage the notch of the firing-pin, the firing-pin being thus locked against movement even if the spring *g*² should be broken.

For the purpose of locking the slide-bar when the gun is taken down, so as to prevent the accidental dropping out of the breech-block, a locking-pin *h*³ is mounted vertically in the side of the receiver *c* and is cut out on one side, as clearly shown in Fig. 2^a, to receive the slide-bar *h*'. The pin is spring-pressed and, when the gun is taken down, projects slightly below the lower edge of the receiver, the upper shoulder of the pin then dropping into a notch *h*⁴ in the upper edge of the slide-bar restraining the slide-bar from rearward movement. When, however, the gun is set up the lower end of

the hammer the upper pin p^3 bears upon the rod-spring s^4 tending to throw the rear end of the slide-latch down and the forward end up, so that as soon as the slide-bar completes 5 its forward movement the latch s' , until then held down by the slide-bar, will snap up back of the end of the slide-bar and prevent rearward movement thereof. When the trigger is pulled and the hammer falls 10 the pin p^4 strikes the under side of the rod-spring s^4 and tends to press the rear arm of the slide-latch up and the forward end down so as to release the slide-bar for the next rearward movement. It will be observed 15 that the provision of two pins on the hammer permits the employment of a single rod-spring on the slide-latch in place of the two flat springs sometimes employed heretofore. It is undesirable, in the event of a 20 hang-fire, that the slide-latch should be released immediately upon the falling of the hammer. The pressure of the rear end of the slide-bar against the front face of the slide-latch, under the influence of the 25 natural rearward pressure of the hand on the grip-piece, tends to prevent such immediate disengagement of the slide-latch. The same effect is produced by the action of the spring g^2 against the firing-pin latch or bell- 30 crank lever g , the lower end of which, under the influence of the spring, presses the slide-bar rearwardly holding it in contact with the face of the slide-latch. The frictional contact between the end of the slide-bar and 35 the slide-latch, whether occasioned by the spring or by the hand, is maintained until the recoil of the gun, when the cartridge is exploded, occasions a slight relative rearward movement of the frame, which carries 40 the slide-latch, with respect to the slide-bar itself, such relative movement being sufficient to release the face of the latch from the end of the slide-bar and permit the latch to fall under the influence of the spring s^4 . 45 In order that the gun may be opened when desired a trip t is pivoted on the trigger-pin r^2 , in front of the trigger, and is movable independently of the trigger to a limited extent. It carries a pin t' which is 50 adapted to make contact with the under side of the rear arm s^3 of the slide-latch, when the trip is pressed forward by the finger, and thereby raise the rear end and depress the forward end of the slide-latch so 55 as to release the slide-bar and permit the opening of the gun. A spring t^2 is interposed between the trip and the forwardly extending toe r' of the trigger to hold the trip normally in an inoperative position. The trip cannot be operated to 60 release the slide-latch when the hammer is pulled because the trigger then swings the trip down so that the pin t' will not make contact with the rear arm of the slide-latch. 65 The trigger cannot be pulled when the trip

is pressed forward because the consequent movement of the slide-latch swings the trigger-latch r^5 under the toe r' of the trigger.

The cartridge-lifter u , by which each cartridge is received from the magazine-tube and is lifted in front of the breech-block so as to be thrust thereby, in its forward movement, into the chamber of the barrel, is pivotally mounted in the assembly clip o on the hammer pivot-pin p' . It comprises the 70 usual spoon-like forward portion u' and a rearwardly extending arm u^2 which carries a roller u^3 , mounted in the end of the arm so as to yield axially against a spring u^4 . In the rearward movement of the breech-block e a beveled portion e^2 of its right hand depending flange presses the roller u^3 inward against the pressure of the spring u^4 and the roller then rides against the inner 75 side of the flange of the breech-block until it slips over the cam-shoulder e^4 . In the forward movement of the breech-block the cam-shoulder engages the roller u^3 and depresses the rear end of the lifter raising the forward end so as to lift the cartridge into 80 line with the chamber of the barrel. The cam-shoulder is formed with a double incline, the first and steeper part e^4 serving to tilt the cartridge and hold it with its forward end in line with the chamber of the 85 barrel, while the second and higher portion e^5 , in the continued movement of the cartridge with the breech-block and after the forward end of the cartridge has entered the chamber of the barrel, serves to lift the rear 90 end of the cartridge into substantial alignment with the barrel so that the friction of the cartridge against the rear edge of the chamber, usual when the lifter has but a single movement, is eliminated. 95

105

It will be obvious that the details of construction and arrangement shown will be varied more or less according to the character of the firearm to which the improvements are applied as well as that the several 110 features of improvement herein shown and described may be employed independently of each other as required by the construction of the firearm to which one or another of such improvements may be applied. 115

I claim as my invention:

1. In a firearm, the combination of a frame having a beveled recess in the under side of its upper wall, and having a rearwardly beveled lug at the forward end of 120 its forward extension, and a receiver having at its rear extremity a beveled hook to engage said recess in the frame, and having in its under side a beveled recess for co-operation with the beveled lug of the frame. 125

2. In a firearm, the combination of a frame having a beveled recess in the under side of its upper wall, and having a beveled lug at the forward end of its forward extension, and having also a ring at the forward end 130

the pin h^3 makes contact with the upper side of the forward portion of the frame and the pin is thereby lifted to take the upper shoulder out of the notch of the slide-bar and so release the slide-bar for movement.

The slide-bar in its reciprocations operates the cartridge cut-off m by which the feed of the cartridges from the magazine-tube is regulated. The cut-off m consists of a rocking bar mounted at m' in a seat formed therefor in the left hand side of the forward lower portion of the frame and provided at its forward end with an inturned 10 lip m^2 which projects far enough toward the axis of the gun to stand in the path of the flange of the next cartridge in the magazine-tube, when the forward end of the cut-off is in its highest position, to prevent the 15 rearward movement of such cartridge under the influence of the spring follower. When the forward end of the cut-off is depressed the flange m^2 stands out of the path of the cartridge which may then move rearwardly 20 upon the lifter. The cut-off is also provided with two lugs m^3 m^4 , rounded at their upper ends and cut away on opposite sides so that the effective portions of the lugs shall stand in different longitudinal planes, 25 the forward lug at the right and the rearward lug at the left. The slide-bar h' is cut away at its lower edge, at the inner or right hand side, as indicated at h^5 , with a cam surface at the rear end of the cutaway 30 portion, and is cut away at its lower edge at the outer or left hand side near its extreme rear end, to form a cam-notch h^6 . When the slide-bar is in its extreme forward 35 position the cut-off occupies the position shown in Fig. 2 with its rear lug m^3 standing in the cam-notch h^6 and its forward lug m^4 pressed down by the slide-bar. As the rearward movement of the slide-bar begins 40 the rear lug m^3 is depressed by the approaching cam surface of the notch h^6 and at the same time the cutaway portion h^5 permits the forward lug m^4 to rise, so that the cut-off is then rocked on its axis to raise the forward end with its lip m^2 into the 45 path of the next cartridge and so prevent the rearward movement thereof. The cut-off retains this position during the remainder of the rearward movement of the slide-bar and during the forward movement thereof 50 until it approaches the limit of its forward movement, when the cut-off will be rocked from the position shown in Fig. 5 to the position shown in Figs. 2 and 4 so as to permit the rearward movement of the next cartridge upon the lifter.

The lock mechanism, including the hammer, trigger, slide-bar latch and lifter, with their associated parts, is mounted, on two pivot-pins, in an assembly clip o , which is 55 fitted to the inside of the frame and may

be secured in place therein by two screws o' . All of the parts of the lock mechanism can be assembled in the assembly clip, outside of the gun, where every part is readily accessible, and can then be placed in the gun 70 as a unit, thus facilitating greatly the work of assembling the gun, either for the manufacturer or for the repairer. The hammer p is mounted on a pivot-pin p' and is acted upon by a main spring p^2 of usual construction. It is cocked by contact with the breech-block in its rearward movement and is held in cocked position by direct engagement with the toe r' of the trigger r which is pivoted in the assembly clip on the trigger-pin r^2 . The trigger is shown as having a rearwardly projecting lug r^3 for coöperation with a notched safety-pin r^4 movable transversely in the trigger-guard. The trigger can be moved only when the notch is in 80 line with the lug.

A yoke-like trigger-latch r^5 , having a bar r^6 to engage the toe r' of the trigger r and hold it from disengagement from the hammer p and having a spring abutment r^7 for 90 coöperation with a light spring r^8 interposed between it and a portion of the slide-bar latch, is hung on the pivot-pin p' of the hammer. It is moved to release position, so that the gun can be fired, only when the 95 slide-latch is itself moved to firing position as the gun is fully closed at the limit of the forward movement of the slide-bar, this movement of the trigger-latch being effected by a shoulder of the slide-latch as herein-after described. Being, however, mounted independently of the slide-latch and subject to the pressure of a spring r^8 , it may yield with respect to the slide-latch, in the movement of the latter, if the trigger should then 100 be held by the pressure of the finger, until such time as the pressure of the finger is released and at such time will be caused by the pressure of the spring r^8 to engage the toe of the trigger and prevent its release. 110

The slide-latch s is also mounted on the hammer-pin p' . It has a forwardly extending stop finger s' , which stands behind the rear end of the slide-bar h' when the gun is in the firing position, as shown in Fig. 2, 115 and thereby prevents the rearward movement of the slide-bar. It carries the small spring r^8 for the trigger-latch, as already described. It is provided also with a shoulder s^2 for coöperation with the rear 120 side of the trigger-latch r^5 to move the same to release position when the slide-bar has completed its forward movement and the slide-latch is permitted to move to firing position. It has also a rearwardly extended 125 arm s^3 which carries a forwardly projected rod-spring s^4 to stand between two pins p^3 , p^4 carried by the hammer p . Toward the close of the rearward movement of the slide-bar and the consequent cocking movement of 130

- of its forward extension, a receiver having at its rear extremity a hook to engage the recess in the frame and having in its under side a beveled recess for coöperation with the 5 beveled lug of the frame, and a magazine-tube threaded into the receiver and having a tapered rear end to coöperate with the ring of the frame.
3. In a firearm, the combination of a frame having a beveled recess in the under side of its upper wall, and having a rearwardly beveled lug at the forward end of its forward extension, the angle between the forward extension and the rear portion of 15 the frame being rounded, and a receiver having at its rear extremity a beveled hook to engage the recess in the frame, and having in its under side a beveled recess for coöperation with the beveled lug of the frame,
- 20 and having its lower rear corners rounded to coöperate with the rounded angle of the frame.
4. In a firearm, the combination of a frame, a receiver, a breech-block, a slide-bar 25 and a locking device for the slide-bar held in position to permit movement of the slide-bar when the frame and receiver are assembled, and movable to lock the slide-bar when the frame and receiver are separated.
- 30 5. In a firearm, the combination of a frame, a receiver, a slide-bar movable in a longitudinal recess in the side wall of the receiver, and a spring-pressed locking pin mounted in the side wall of the receiver and 35 adapted to engage the slide-bar to prevent movement thereof and to be held out of locking engagement by contact with the frame when the frame and receiver are assembled.
6. In a firearm, the combination of a receiver, a magazine-tube, a frame, and a cartridge cut-off mounted to rock on the frame and having at its forward end a lip to stand in the path of the cartridge when elevated, and having on its upper edge two lugs with their 45 upper ends in different longitudinal planes, the slide-bar being cut away on its lower edge in different longitudinal planes to coöperate with the lugs of the cut-off.
7. In a firearm, the combination of a frame having an integral trigger-guard, an assembly clip detachably secured in the frame and located wholly within the same, a lock mechanism supported wholly on the assembly clip and removable therewith from 55 the frame.
8. In a firearm, the combination of a frame having an integral trigger-guard, an assembly clip detachably secured in the frame and located wholly within the same, 60 and a hammer, a trigger and a main spring mounted in the frame and removable therewith.
9. In a firearm, the combination of a frame, a slide bar, an assembly clip detachably secured in the frame, and a hammer,
- a main spring, a slide-latch and a trigger mounted in the assembly clip and removable therewith from the frame.
10. In a firearm, the combination of a frame, a slide bar, an assembly clip detachably secured in the frame, a hammer pivot-pin and a trigger pivot-pin mounted in the clip, a hammer and a slide-latch mounted on the hammer pivot-pin, and a trigger and a slide-latch trip mounted on the trigger 75 pivot-pin.
11. In a firearm, the combination of a frame a slide bar, an assembly clip detachably secured in the frame, a hammer pivot-pin and a trigger pivot-pin mounted in the 80 clip, a hammer, a slide-latch and a trigger-latch mounted on the hammer pivot-pin, and a trigger and a slide-latch trip mounted on the trigger pivot-pin.
12. In a firearm, the combination of a frame, a slide bar, an assembly clip detachably secured in the frame, a hammer pivot-pin and a trigger pivot-pin mounted in the assembly clip, a hammer, a slide-latch and a lifter mounted on the hammer 90 pivot-pin, and a trigger and a slide-latch trip mounted on the trigger pivot-pin.
13. In a firearm, the combination of a slide-bar, a slide-latch standing normally against the rear end of the slide-bar, and a 95 spring-pressed lever acting upon the slide-bar to hold its rear end normally in contact with the face of the slide-latch.
14. In a firearm, the combination of a hammer, a slide-bar, a slide-latch, a trigger 100 and a slide-latch trip, the trip being pivoted on the same axis with the trigger and in advance thereof.
15. In a firearm, the combination of a hammer, a slide-bar, a slide-bar latch, a 105 trigger, and a trigger-latch, the slide-bar latch coöperating with the trigger-latch to release the trigger when the slide-bar latch is in firing position.
16. In a firearm, the combination of a frame, a slide-bar, a slide-bar latch, a trigger and a spring-pressed trigger-latch, the trigger-latch being mounted on the same axis with the slide-bar latch but independently thereof, and the slide-bar latch having 115 a shoulder for coöperation with the trigger-latch to move the same to release the trigger.
17. In a firearm, the combination of a hammer, a slide-bar, a slide-bar latch, a trigger and a spring-pressed trip for the slide-bar latch, the trip being mounted on the same axis with the trigger but independently thereof.
18. In a firearm, the combination of a frame, a receiver, a slide-bar, a breech-block 125 having two successive cam inclines at different angles, and a cartridge lifter having a roller to be engaged by said inclines in succession in the forward movement of the breech-block.

19. In a firearm, the combination of a frame, a receiver, a slide-bar, a breech-block having a depending wall formed with a beveled surface at its rear end and with a cam-track forward of its rear end, and a cartridge lifter having a rearwardly extended arm with a laterally yielding roller adapted to be engaged by the beveled edge of the cam-block and to be pushed to one side thereby in the rearward movement of the breech-block to operate the lifter.

20. In a firearm, the combination of a frame, a slide-bar, a slide-latch in the path of movement of the slide-bar, and a spring-pressed lever acting upon the slide-bar to

hold it in frictional contact with the slide-latch to hinder releasing movement of the slide-latch until the cartridge is exploded.

21. In a firearm, the combination of a frame, a slide-bar, a slide-latch in the path of movement of the slide-bar, a firing-pin, and a spring-pressed lever to engage the firing-pin to prevent effective movement thereof and acting upon the slide-bar to hold it in frictional contact with the slide-latch to hinder releasing movement of the slide-latch until the cartridge is exploded.

This specification signed this 15th day of August, A. D. 1916.

EDWARD E. REDFIELD.
